GOLF BAG SUPPORT

Joseph Staugaitis, Elmwood Park, Ill.

Application July 7, 1939, Serial No. 283,246

1 Claim. (Cl. 248—96)

The invention relates generally to golf bag supports, and more particularly it relates to such supports adapted to support the golf bag in a partially elevated position while the player is making a shot on the golf course.

The primary object of the invention is to provide a new and useful golf bag support of this character which is simple in construction, light in weight, and effective in use.

10 A further object is to provide such a new and useful golf bag support which is compact in design and which normally occupies an out-of-the-way position so as not to interfere with the carrying of the bag between shots.

15 Another object of the invention is to provide such a new and useful golf bag support which is easily and readily applied to conventional golf bags.

20 Other objects and advantages will become apparent from the following description, taken in connection with the accompanying drawing, in which:

Fig. 1 is a perspective view showing a golf bag support embodying the features of the invention, with the bag supported in its angular but generally upright position.

25 Fig. 2 is a fragmental elevational view of a portion of the support.

Fig. 3 is a fragmental sectional view taken substantially along the line 3—3 of Fig. 2.

Fig. 4 is a fragmental sectional view taken substantially along the line 4—4 of Fig. 2.

Fig. 5 is a fragmental elevational view similar to Fig. 2 and showing an alternative form of the support.

Fig. 6 is a fragmental sectional view taken substantially along the line 6—6 of Fig. 5.

For purposes of disclosure, I have illustrated in the drawing and will hereinafter describe in detail two preferred embodiments of the invention, with the understanding that I do not intend to limit my invention to the particular constructions and arrangements shown, it being understood and contemplated that various changes may be made by those skilled in the art without departing from the spirit and scope of the invention as defined by the appended claim.

In the form chosen for disclosure in Figs. 1 to 4 of the drawing the invention is embodied in a golf bag support 10 shown in its operative relation on a golf bag 11. The bag 11 may take any of the conventional forms, the one herein shown being relatively small and round in cross section with a protective covering or boot 12 at

its closed or bottom end to protect the lower portion of the outer side wall 13 of the bag.

The outer side wall 13 may have one or more inner liners 14, as shown in Fig. 3, and at its upper end is bent inwardly about a top ring 15 and is secured thereabout by means such as stitching 16. Thus an open upper or top end 17 is formed to receive clubs such as the clubs 18. A suitable handle 19 is secured to one side of the bag, near the top end or open end 17 of the bag, and for present purposes the "handle" side of the bag will be termed the "upper" side of the bag.

In accordance with the present invention the bag 11 may be supported in a conveniently accessible angular relation to the ground, as shown in Fig. 1, by the supporting device 10, and this supporting device is of such a character that it is economical as well as sturdy in construction, and is exceptionally convenient in use. To this end the support 10 comprises an attachment bracket 20 adapted for convenient and rapid mounting on golf bags of different sizes and constructions, and with the bracket 20 there is pivotally associated a supporting leg 21. The leg 21 is adapted to be moved from a normally inactive position along the lower side of the bag (Fig. 3) to an angular operative relation to the bag (Fig. 1) wherein the leg 21 may be thrust into the ground to support the bag in the desired partially upright position. The angularity of the bag when thus supported depends, of course, upon the depth to which the leg 21 is thrust into the ground, and may be varied by the length of the leg 21, as well as by the relative length of the golf bag.

The bracket 20 is preferably formed from an elongated strip of sheet metal, having apertured attachment ears 22 at its opposite ends, and in mounting the bracket 20 on a bag 11 suitable registering openings 23 are formed in the walls 13 and 14 so that headed bolts 24 may be passed through the walls and through the openings in the attachment ears 22. Preferably a washer 25 is positioned between the head of each bolt 24 and the inner wall 14 (Fig. 4) and a nut 26 is screwed onto the outer ends of the bolts 24 to clamp the bracket 20 firmly against the outer face of the wall 13. While the bracket is herein shown as being located closely adjacent to the top end 17 of the bag, it will be evident that it could be located downwardly a considerable distance on the side of the bag.

To provide a pivotal connection between the bracket 20 and the leg 21, suitable spaced bear-

ing members 30 are provided on the bracket 20 and in the form shown in Figs. 1 to 4, these bearing members 30 comprise lugs cut from the sheet metal of the bracket and bent to outward 5 projecting positions substantially at right angles to the main body or plane of the bracket, and at a substantial distance apart. The members 30 as herein shown are formed from the portions of the sheet of metal which would normally project along the sides of the ears 22, and when each ear is bent outwardly to the desired projecting relation, the two ears are in parallel relation to each other. The bearing members 30 are formed with alined openings 31 substantially 10 centrally thereof, which openings 31 serve as bearings for the pivotal mounting of the leg 21 on the bracket 20; and since it is desired that the leg 21 move substantially in a plane passing through the central axis of the bag 11, the bracket 20 is so positioned on the bag 11 that the axis of the bearing openings 31 is transversely related to the longitudinal axis of the bag 11.

In accordance with the present invention the leg 21 is formed from a round, relatively stiff 25 metallic rod which is sharpened as at 35 at its lower end to facilitate insertion thereof into the ground; and the leg is formed at its upper end to cooperate with the bearing members 30 in attaining the desired pivoted mounting of the leg 21 on the bracket 20. In attaining this purpose the upper end of the leg 21 is bent to provide an integral bearing portion 36, located at right angles to the main body of the leg, and this bearing portion is adapted to project 30 through the bearing openings 31 in the two bearing members 30. In order that the leg 21 may be positioned in a plane passing substantially midway between the bearings 30 and at right angles to the bearing axis, the bearing 35 portion 36 is formed by first bending the leg to one side as at 37 to form an angular portion 38 which at 39 is bent back to a parallel relation to the leg 21 to form a short connecting portion 40, and then is bent at right angles to the connecting portion 40, as at 41, to form the bearing portion 36. At its opposite end the bearing portion 36 is bent to a similar form, to provide a connecting portion 40', an angular portion 38', and an end portion 42 which extends 40 for a short distance parallel and adjacent to the leg 21 below the bend 37. Thus the leg 21 has a generally triangular head portion which is integrally formed and provides a bearing connection with the bracket 20.

About the bearing portion 36 of the leg 21 a spiral torsion spring 45 is mounted, the spring, as shown in Figs. 2 and 3, being located between the two bearing members 30, and one arm of the spring, designated as 46, is hooked over the upper edge of the bracket 20 as shown at 47 in Fig. 3. The other arm 48 of the spring 45 is wound at 49 about the angular portion 38' of the leg

in spaced relation to the axis of the bearing portion 36. The spring 45, therefore, acts to urge the leg 21 from the active position of Fig. 1 to the inactive, out-of-the-way position of Fig. 3, wherein the leg lies along the lower side surface of the bag 11.

In the form shown in Figs. 5 and 6 the invention is embodied in a golf bag support generally like that of Figs. 1 to 4, but with a simplified form of bracket 20'. This bracket 20' is formed 10 from a simple strip of sheet metal secured to the bag 11 by bolts 24' in the same general manner as the bracket 20. To provide bearing means for the leg 21, the bracket 20' has spaced openings 50 formed therein to receive bearing members 51. These bearing members 51 are in the form of circular bands bent from half-round metal bands to embrace the bearing portion 36 of the leg 21, and having attachment portions 52 adapted to project through the openings 50. 15 These attachment portions 52 are bent apart behind the bracket 20', as shown in Fig. 6 to secure the bearings 51 in position on the bracket 20'. The generally triangular head portion of the leg 21 in Figs. 5 and 6 is substantially the same as in Fig. 1, except that the connecting portions 40 have been eliminated. A similar spring 45' is mounted about the bearing portion 36 of the leg 21, with one arm 48' thereof hooked about one of the angular portions of the head of the leg 21, 20 and the other arm 46' engaged with the bracket 20'. Thus the leg 21 in Figs. 5 and 6 is normally urged toward an inactive position in the same general manner as the leg 21 in the other form.

From the foregoing it will be apparent that the invention provides a new and improved golf bag support which is simple in construction, and convenient in use.

I claim as my invention:

A golf bag support comprising, in combination, 40 a bracket adapted to be placed against the outside of a golf bag adjacent to the upper end thereof and having apertured attachment ears formed at opposite ends thereof, a pair of bearing members projecting outwardly from said bracket in spaced relation to each other and having alined bearing openings formed therein, a leg formed from a round and relatively stiff rod sharpened at one end and formed at its other end to provide a bearing portion extending at 45 right angles to the main portion of the leg and projecting through both of said bearing members, said bearing portion being bent to retain said bearing portion in the desired operative relation to said bearing members, and a torsion spring surrounding said bearing portion between said bearing members and having one arm engaging said bracket and the other arm engaging said leg in spaced relation to the axis of said bearing portion. 50

JOSEPH STAUGAITIS.
